UNITED STATES PATENT OFFICE

WALTER E. MILEY, OF MARION, OHIO, ASSIGNOR TO THE MARION STEAM SHOVEL COMPANY, OF MARION, OHIO, A CORPORATION OF OHIO

EXCAVATING DIPPER

Original application filed February 21, 1927, Serial No. 169,786. Divided and this application filed September 12, 1927. Serial No. 218,944.

This invention relates to excavating dippers of the type commonly employed in connection with power operated shovels.

One object of the invention is to provide a dipper made up of a plurality of parts or sections which will be simple in its construction and of a very strong durable character; and which will be of such a character that it may be made either entirely of cast metal parts or of a combination of cast metal parts and plates.

Another object of the invention is to provide such a dipper with a bail bracket of a strong durable character in which the openings for the bail pins will be maintained permanently in alinement; and in which the bail brackets will be so connected with the dipper front as to cause the lifting strains to be imposed on the front.

Another object of the invention is to provide such a dipper with means for protecting the bail brackets from injury or wear due to contact with the material in which the dipper is working.

Other objects of the invention will appear as the device is described in detail.

In the accompanying drawings Fig. 1 is a side elevation, partly in section, showing a dipper embodying my invention; Fig. 2 is a plan view of such a dipper, partly broken away; Fig. 3 is a detail view of the top bar; Fig. 4 is a side elevation of the dipper front; Fig. 5 is a side elevation of the lower portion of the side member; Fig. 6 is a side elevation of the protector for the bail bracket; Fig. 7 is a top plan view of one of the bail brackets and its protector; Fig. 8 is a vertical sectional view taken through the bail bracket and protector; Figs. 9, 10, 11 and 12, show a slightly modified form of the dipper, Fig. 9 being an edge view of the dipper back, Fig. 10 being a side elevation of the one-piece side member, Fig. 11 being a bottom plan view of the same, and Fig. 12 being a side elevation, partly in section, of the dipper front; Fig. 13 is a plan view of a portion of the dipper back; Fig. 14 is a plan view of the side member; Fig. 15 is a plan view of a portion of the front; Fig. 16 is a side elevation of one of the side members of another modified form of the dipper; Fig.

17 is a side elevation of one of the bail brackets; Fig. 18 is a side elevation of the dipper front; Fig. 19 is a plan view of the side member of Fig. 16; Fig. 20 is a plan view of the separate bail bracket of Fig. 17; Fig. 21 is a plan view of a portion of the front of Fig. 18; Fig. 22 is a front elevation of a portion of the dipper showing a modified form of protector for the bail bracket; and Fig. 23 is a side elevation of the device shown in Fig. 22.

The present application is a division of the application filed by me February 21, 1927, Serial No. 169,786.

In these drawings I have illustrated one embodiment of my invention together with certain modifications thereof. The several parts of the dipper are of such a character that the dipper may be made entirely of cast metal parts or may be made partly of cast metal parts and partly of plates, the construction being such that either material may be used without change of design. The modifications consist for the most part of such changes as are necessary to enable the side members to be made in one or more parts with the bail brackets integral with or separate from the side members. It will be understood that the embodiment here shown has been chosen for the purposes of illustration only and that the various modifications are merely typical of changes which may be made without departing from the spirit of the invention.

As a matter of convenience in the description the terms "upper" and "lower", as used in connection with the dipper, have reference to the dipper in the position shown in Fig. 1, in which the dipper front is in a vertical position.

Having reference more particularly to Figs. 1 to 5 the dipper comprises a front 1, which is slightly curved in shape and is provided with rearwardly extending side portions 2, and mounted at the upper or cutting edge of the front are the usual teeth 3. Inasmuch as this front is subjected to very severe wear it is usually made of cast metal, manganese steel being preferable for this purpose. The dipper back is shown at 4 and carries the usual lugs for connecting the same with the dipper arm and for pivotally

supporting the door as will hereinafter appear. Because of the strains imposed thereon the back also is usually a casting. The front and back are connected one to the other by side members which may be either castings or plates and which, further, may be formed in one part or in more parts. As shown in Fig. 1 the side member comprises a lower portion 5 and an upper portion or top bar 6. The side member as a whole overlaps and is rigidly secured to the back 4, preferably by means of rivets, and the forward portions of the side members overlap the respective side portions of the front and are rigidly secured thereto by rivets or the like. The front and rear portions of the side members may be recessed on their inner sides, as shown at 7, to cause the connected portions of the back and front to lie substantially flush with the inner surfaces of the side members. Arranged on the respective sides of the dipper are bail brackets 8 to receive the arms of the bail by means of which the dipper is elevated. As here shown, each bail bracket comprises an outer portion 9 and an inner portion 10 formed in one piece with the outer portion so that the openings to receive the bail pin may be properly aligned one with the other and will remain permanently in their properly aligned positions. Usually the outer portion of the bail bracket is separate from the inner portion thereof and the inner portion thereof comprises a part of the side member or front of the dipper to which the outer portion of the bracket must be riveted. As a result it is very difficult to obtain the proper alignment of the pin opening in the bracket with the pin opening in that part of the dipper to which the bracket is riveted. Moreover, due to the severe service to which these dippers are subjected the outer portion of the bracket will frequently become loose, thus causing breakage and delay. By providing a complete bracket consisting of inner and outer portions formed in one piece the pin openings may be very easily aligned when the bracket is made and there is no possibility of their getting out of alignment. I also prefer that the bail bracket as a whole should be formed in one piece with the adjacent part of the dipper and, as shown in Figs. 2 and 3, the bail bracket is cast integral with the top bar 6 of the adjacent side member of the dipper. As here shown, the top bar has at its forward end a downwardly extending portion, or enlarged portion, 11 and the bail bracket is cast integral with this part of the bar. That part of the bar by which the bail bracket is carried overlaps the rearwardly extending side portion 2 of the front and is rigidly secured thereto by rivets. However, it is desirable that the bail brackets be so connected with the dipper front that the severe strains imposed thereon will be

transmitted from the brackets directly to the front, and the rivets connecting these parts will not be subjected to shearing strains. For this purpose the bail bracket and the adjacent portion of the front are provided with interlocking parts so arranged that the thrust on the one part will be transmitted directly to the other. As here shown, the inner portion of the bail bracket is provided with an inwardly extending lug which is preferably in the form of a boss 12 cast integral therewith and which, when the parts are in their assembled position, extends through an opening 13 in the rearwardly extending part of the front, this opening having a bearing surface 14 with which the lug or boss 12 contacts.

The bail brackets necessarily project from the sides of the dipper and the arrangement is such that they come in contact with the material in which the dipper is working and are subjected to very severe wear and are liable to breakage. To protect the bail brackets from this severe wear I have arranged on each side of the dipper, in advance of the bail brackets, a guard 15, (see Figs. 6, 7 and 8). This guard may take various forms but, as here shown, it comprises a body portion or plate overlying the outer side of the bail bracket and having at its forward and lower edges a flange 16 which lies below and in front of the bail bracket and is rigidly secured to the side of the dipper. The guard is preferably provided at its upper edge with an inwardly extending flange 17 which overlies the upper and rear edges of the outer portion 9 of the bracket. The rear portion of the guard is spaced from the adjacent side member of the dipper so as to provide an opening at the rear of the bracket to receive the bail when the dipper front approaches a horizontal position, and through which may escape any material which may enter the guard. The guard is also provided with an opening, such as a slot 18, arranged in line with the pin openings of the bracket so that the bail pin may be removed without removing the guard.

As has been stated, this guard may take various forms and in Figs. 22 and 23 I have shown a guard which is mounted on the bail 19 and is so arranged with relation to the bail bracket that it will lie in front of that bracket. As here shown, the guard comprises a curved body 20 which is rigidly secured to the bail above the bracket and is provided with a depending flange 21 which overlies the upper portion of the bracket. The body portion of the guard extends for some distance in front of the bail and the guard as a whole is so arranged that it will lie in advance of and overlap the bracket in all operative positions of the bail and the dipper.

The dipper is provided at its lower or discharge end with a door 29 which, in the pres-

ent construction, is carried by arms 30, the rear ends of which are curved upwardly and pivotally mounted on the dipper back 31, the arrangement being such that the door will have swinging movement into and out of a position to close the lower end of the dipper. The door is provided with a latch bar 32 adapted to engage a latch plate 35 on the dipper front to hold the door in its closed position. The latch plate may be mounted on the front in any suitable manner, but as shown in Fig. 1, the dipper front has in its lower edge a recess 36, a portion of which opens entirely through the front, and the latch plate 35 is mounted in this recess, the plate and the front having overlapping portions which are rigidly connected one to the other by rivets or otherwise. The latch plate has an opening 40 extending through the same to receive the latch bar 32 and the lower portion of the latch plate is beveled at 136 to engage the end of the latch bar and retract the same as the door moves to its closed position.

The several major parts of the dipper may take various forms, this being particularly true with relation to the side members, each of which may consist of a single part or of a plurality of parts and which may have the bail brackets formed either in one piece therewith or separate therefrom and rigidly secured thereto. In Figs. 9 to 15 I have shown a second form of the dipper in which the front 44 and the back 45 are of substantially the same construction as shown in Figs. 1 and 2 but the side member 46 is formed of a single part, it being either made from a single piece or fabricated from plates or sheets. The general shape and arrangement of the parts is substantially the same as that of the side member shown in Fig. 1 with the exception that the top bar is integral with the lower portion of the side member. Bail brackets 47 have their inner and outer portions formed in one piece with each other and in one piece with the side member 46. The inner portion of the bail bracket has a lug or boss 12 arranged to enter the opening 13 in the adjacent side portion of the front. In these drawings the guard for the bail bracket is not shown but the front is provided with a seat or pad 48 on which the guard may be mounted.

In that arrangement of the dipper parts shown in Figs. 16 to 21 the side member 50 is in one piece, it being here shown as fabricated from plates and bars, and it has at its upper end a forwardly extending part 51 adapted to extend on the inner side of the rearwardly extending side portion 52 of the front 53. The bail bracket 54 is in this instance formed separate from the other parts of the dipper and is mounted on the side portion of the front and on the side member, the bail bracket, front and side member being rigidly connected one to the other by rivets.

The inner and outer portions of this bail bracket are formed in a single piece and the inner portion has a stud or boss 12 to enter the opening 13 in the side portion of the front. The part 51 of the side member has an opening 55 in line with the pin openings 56 of the bail bracket to facilitate the removal of the pin.

While I have shown and described one embodiment of my invention, with certain modifications thereof, I wish it to be understood that I do not desire to be limited to the details thereof as various modifications may occur to a person skilled in the art.

Having now fully described my invention, what I claim as new and desire to secure by Letters Patent, is:

1. In an excavating dipper, a front, a back, side members connecting said front with said back, bail brackets carried by the respective side members and each comprising inner and outer portions formed in one piece and having aligned openings for the bail pin, the inner portion of each bracket and said front having interlocking parts to transmit the strain from the bracket to the front.

2. In an excavating dipper, a front, a back, side members connecting said front and said back, and bail brackets each comprising inner and outer members formed in one piece with one of said side members and having aligned openings to receive a bail pin, said inner portions of said brackets and said front having interlocking parts to transmit the strain from said bracket to said front.

3. In an excavating dipper, a front, a back, side members connecting said front and said back, bail brackets each comprising inner and outer members formed in one piece and having aligned openings to receive a bail pin, the inner portion of each bracket and said front having interlocking parts to transmit the strains from said bracket to said front.

4. In an excavating dipper, a front having rearwardly extending side portions each having an opening near the upper edge thereof, a back, side members connecting said front and said back, and bail brackets carried by said side members and having parts overlapping and secured to the respective side portions of said front and having lugs extending into the openings in said side portions.

5. In an excavating dipper, a front having rearwardly extending side portions each having an opening near the upper edge thereof, a back, side members connecting said front and said back, and bail brackets each comprising inner and outer portions formed in one piece and having aligned openings to receive a bail pin, the inner portion of each bracket overlapping and secured to one of the side portions of said front and having a boss arranged about said pin opening and extending into the opening in said side portion of said front.

6. In an excavating dipper, a front having rearwardly extending side portions each having an opening near the upper edge thereof, a back, side members connecting said front and said back, and bail brackets each comprising inner and outer portions formed in one piece with one of said side members and having aligned openings to receive a bail pin, the inner portion of each of said brackets overlapping and secured to a side portion of said front and having a boss arranged about said pin opening and extending into the opening in said side portion. 70
10. 7. In an excavating dipper, a front having rearwardly extending side portions, a back, side members connecting said front and said back, each of said side members comprising a lower portion and a top bar rigidly secured to said lower portion, bail brackets arranged on the respective sides of said dipper and each comprising inner and outer portions formed in one piece and carried by the top bar of the adjacent side member. 80
20. 8. In an excavating dipper, a bail bracket carried by said dipper, and a guard arranged in advance of said bail bracket to protect the same from injury by contact with the material in which said dipper is working, said guard being mounted independently of and spaced from said bail bracket. 90
30. 9. In an excavating dipper, a bail bracket carried by said dipper, and a guard mounted on said dipper independently of said bracket and having portions arranged in front of and above said bail bracket. 100
35. 10. In an excavating dipper, a bail bracket carried by said dipper, and a guard rigidly secured to said dipper in front of said bail bracket and extending rearwardly along the outer side of said bracket in spaced relation thereto. 105
45. 11. In an excavating dipper, a bail bracket carried by said dipper, and a guard rigidly secured to said dipper in front of said bail bracket and extending outwardly beyond said bracket and then rearwardly along the outer side of said bracket, said guard also having a portion extending inwardly above the outer portion of said bracket and spaced therefrom. 110
50. 12. In an excavating dipper, a bail bracket carried by said dipper and a guard rigidly secured to said dipper in front of said bail bracket and extending rearwardly along the outer side of said bracket in spaced relation thereto and having an opening in line with the pin opening in said bracket. 115
60. 13. In an excavating dipper, a front having rearwardly extending lateral portions, a back, side members secured at their rear edges to said back and at their forward edges to the respective lateral portions of said front, bail brackets rigidly supported by said side members and said lateral portions of said front on the respective sides of said
65. dipper, and guards rigidly secured to the respective lateral portions of said front and to the respective side members and extending over the outer sides of the respective bail brackets. 75
70. 14. In an excavating dipper, a front having rearwardly extending lateral portions, a back, side members secured at their rear edges to said back, and at their forward edges to the respective lateral portions of said front, bail brackets rigidly supported by said side members and said lateral portions of said front on the respective sides of said dipper, guards rigidly secured to the respective lateral portions of said front and to the respective side members and extending over the outer sides of the respective bail brackets, the rear portions of said guards being spaced from the respective side members to provide openings. 80
75. 15. In an excavating dipper, a front having rearwardly extending side portions, a back, and side members connecting said front and said back, each of said side members comprising a lower portion and an upper portion formed separate from the lower portion, and bail brackets carried by said upper portions of the respective side members. 90
80. 16. In an excavating dipper, a front having rearwardly extending side portions, a back, side members connecting said front and said back, each of said side members comprising a lower portion and a top bar formed separate from the lower portion and having an enlarged part at its forward end, and bail brackets carried by said enlarged parts of the respective top bars. 100
85. 17. In an excavating dipper, a front having rearwardly extending side portions, a back, side members connecting said front and said back, each of said side members comprising a lower portion and a top bar formed separate from the lower portion and having an enlarged part at its forward end, and bail brackets formed in one piece with said forward end portions of the respective top bars. 110
90. 18. In an excavating dipper, a front having rearwardly extending side portions, a back, side members connecting said front and said back, each of said side members comprising a lower portion and a top bar formed separate from the lower portion, the forward ends of said top bars overlapping the respective side portions of said front, and bail brackets each formed in one piece with the forward end portions of one of said top bars, said top bars and said side portions of said front having interlocking parts. 120
95. 19. In an excavating dipper, a front having rearwardly extending side portions, a back, side members connecting said front and said back, each of said side members comprising a lower portion and a top portion, both parts of said side members being rigidly secured to said back and to the rearwardly 130

extending portions of said front, and a door hinged to said back and movable into and out of a position to close the lower end of said dipper.

- 5 20. In an excavating dipper, a front having rearwardly extending side portions, a back, side members connecting said front and said back, each of said side members comprising a lower portion rigidly secured 10 at its front and rear edges to said back and to one of the rearwardly extending side portions of said front and also comprising a top bar rigidly secured at its rear end to said back and at its front end to the rearwardly 15 extending side portion of said front and also rigidly secured to the lower portion of said side member, and a door hinged to said back and movable into and out of a position to close the lower end of said dipper.
- 20 In testimony whereof, I affix my signature hereto.
